UNITED STATES PATENT OFFICE.

RUDOLF E. HELLMUND, OF SWISSVALE, PENNSYLVANIA, ASSIGNOR TO WESTINGHOUSE ELECTRIC & MANUFACTURING COMPANY, A CORPORATION OF PENNSYLVANIA.

MEANS FOR AND METHOD OF ACCELERATING INDUCTION MOTORS.

1,417,731.

Specification of Letters Patent. Patented May 30, 1922.

Application filed August 10, 1918. Serial No. 249,335.

To all whom it may concern:

Be it known that I, RUDOLF E. HELLMUND, a subject of the German Empire, and a resident of Swissvale, in the county of Allegheny and State of Pennsylvania, have invented a new and useful Improvement in Means for and Methods of Accelerating Induction Motors, of which the following is a specification.

10 My invention relates to means for, and methods of, accelerating induction motors which are operated in conjunction with a variable primary frequency, especially if single-phase frequency changers are used.

15 In the operation of motors of the above character, in connection with combined single-phase frequency changers and phase converters, certain difficulties are experienced on account of the higher harmonic 20 secondary currents of such frequency changers. These currents will, when allowed to pass into the main machine, produce therein counter-torques at certain speeds. These speeds may often be predetermined and I 25 have discovered that, if, at these speeds, the ratio of voltage to frequency be raised an appreciable amount, these points of low torque may be passed without interfering with the acceleration of the motor or other harmful 30 effects being noticed. However, unless the effects of the counter-torques are nullified, the large resultant currents at the critical speeds give undesirable heating and low efficiency of operation for a given torque.

35 In determining the particular speeds at which the above-described counter-torques are most pronounced, use is made of the fact that only odd harmonic currents are effective in causing the undesirable fields. The single- 40 phase magnetomotive forces which are impressed upon a machine can be resolved into two oppositely rotating magnetomotive forces and the fields produced in the stator members, rotate with the speed of $R-S$ and 45 $R+S$, S being the synchronous speed of the rotor member of the machine and R being the actual speed of said member. The currents which are produced by these fields are commutated into currents having a fre-

quency of $fr-s$ and $fr+s$, fr being equal to 50 the rotational frequency and f being equal to the line frequency.

If the machine in question is operated at under synchronous speed, $fr < f$ and, therefore, $fr-f$ is negative. It follows that the 55 algebraic difference of the two commutator frequencies is always $2f$. Assuming now that one of the currents derived from the commutator has a frequency of f_1 , the other current derived therefrom will be equal to $2f-f_1$, the resulting main motor synchronous speeds being proportional to the latter figure.

If we now assume the condition that the motor must run at approximately synchronous speed corresponding to the frequency f_1 , and, moreover, at approximately the synchronous speed corresponding to $\frac{1}{n}$ of the frequency $2f-f_1$, we have

$$f_1 = \frac{2f-f}{n}$$

or

$$f_1 (1+n) = 2f$$

and

$$\therefore f_1 = \frac{2f}{1+n}$$

where n may be any whole odd integer, since, as hereinbefore pointed out, it is well-known that only the odd harmonic currents set up undesirable fields. Assuming, for instance,

that $n=5$, we have $f_1 = \frac{f}{3}$ and $2f-f_1 = \frac{5}{3}f$.

The result is that a motor running at a speed corresponding to synchronism of one of the frequencies, at the same time, is running at a speed corresponding to one-fifth of the other frequency. Therefore, the motor has a 90 backward torque component at one-fifth speed and the resultant torque in this region of the acceleration range is, therefore, lowered.

I propose, therefore, to so arrange a system of induction-motor control that none of these critical low-torque speeds are used as running speeds and, at the same time, that

the ratio of voltage to frequency is increased while going through said speeds. Such an increase will result in a temporarily stronger main motor field and this will tend, in a large measure, to compensate for the loss in torque caused by the higher harmonic currents passing into the main motor from its association frequency-changer secondary.

Referring to the drawings, in which a system for the practice of my method of operation is shown, Figure 1 is a circuit diagram illustrating the control used. Fig. 2 is a graphic chart illustrating the manner in which the ratio of voltage to frequency is changed. Fig. 3 is a sequence chart illustrating the switching operations necessary to obtain increased voltages in connection with the system shown in Fig. 1. Fig. 4 is a view similar to Fig. 1 but illustrating a modification of the system, while Fig. 5 is a graphic ratio chart covering the operation of the system shown in Fig. 4; and Figs. 6 and 7 are switching sequence charts illustrating the operation of the switches necessary to produce the ratios shown in Fig. 5.

Referring now more particularly to the drawings, an induction motor 25, having a squirrel-cage secondary 26 and a phase-wound primary 27, is shown as supplied with energy through a frequency-changer 30, which consists of a rotor 31 and stator members 32-32. The rotor of the frequency changer is provided with slip rings 33 and a commutator 34, the slip rings 33 being connected to a source of supply, here shown, for convenience, as the secondary 36 of a transformer 37. An auxiliary driving machine 35 is provided to operate the frequency changer 30. Switches 1 to 9, inclusive, are arranged in conjunction with inductive devices 38 and 39 for the purpose of voltage control.

Referring now to Fig. 2, the manner in which it is necessary to increase the ratio of voltage to frequency is illustrated. The lines 64-65 and 66-67 indicate those frequencies at which it has been predetermined there is an excess of higher harmonic currents passing into the main induction motor and in such manner as to cause points of low torque therein. In order, therefore, to adequately accelerate the motor beyond this point, it is necessary that, at such points, an increased ratio of voltage to frequency shall be obtained. For instance, in Fig. 2, it will be observed that the line 50-51 is that line at which each of the lines representing frequency change would normally end. The frequency and voltage steps must therefore be so selected that none of the increases in frequency will fall to the right of the line 50-51, since, if such a condition were present, the motor would work with too weak a field and might fail to accelerate beyond that speed, especially if an appreciable

counter-torque should exist near this speed.

In the operation, therefore, of a system arranged in accordance with my invention, a switching sequence, as illustrated in Fig. 3, is used, and the voltage and frequency are raised in accordance with the chart above referred to and illustrated in Fig. 2. The frequency changer is first operated at its highest speed, that is, slightly below synchronization, with the switches 3 and 4 closed and its voltage adjusted for the lowest value by the closing of switches 5 and 6. The steps illustrated by lines 50-52 and 52-53 have then been taken and the main motor is operating at a voltage corresponding to the point 53. After the motor has been accelerated, under these conditions, as far as possible, and further acceleration is desired, the switches 2 and 3 are first closed to lower the speed of the frequency changer and thus to raise the frequency and the motor speed until point 54 on the line 50-51 is reached, this being a running point. To further accelerate the motor, the voltage is first raised by closing the switches 6 and 7. Switches 1 and 2 are then closed to lower the speed of the frequency changer and thereby gradually increase the secondary frequency. It will be noted that, by this operation, the critical point, indicated by the line 64-65, will be passed with a greatly increased ratio of voltage to frequency. The next point of low torque, namely, that indicated by the line 66-67, is passed in a similar manner, as may be seen by reference to the sequence chart in Fig. 3.

In Fig. 4, a system of acceleration is illustrated wherein the normal ratio of voltage to frequency is indicated by a line which does not pass through the intersection of the co-ordinates, that is, a line as illustrated at 51-52.

This system gives, for even normal operation, a somewhat increased ratio of voltage to frequency for the lower frequencies, such operation being desirable because of the fact that the ohmic drops at these lower frequencies represent a higher percentage of the total motor voltage and also that, with these lower frequencies, a somewhat stronger field is both permissible and desirable to give minimum motor heating under all conditions.

The switching sequence used under these circumstances is shown in Fig. 6 and is similar to that illustrated in Fig. 3.

However, I have, in addition, illustrated in the graphic chart shown in Fig. 5 and in the sequence chart shown in Fig. 7, a method of even further increasing the abnormal ratio of voltage to frequency and, after thus passing the critical points, returning to normal ratio. In Fig. 5, these abnormal ratio increases are shown in the dotted lines. By the use of this latter method of accelera-

tion, points of very decided counter-torque may be passed without interfering with the normal operation of the motor.

While I have shown but two modifications 5 of a system for accelerating an induction motor in accordance with my invention, I do not desire to be limited to the specific means shown herein, since it is entirely possible that other combinations may be used 10 for passing the hereinbefore described points of low torque without departing from the scope of my invention. I desire, therefore, that the appended claims shall be construed as broadly as the prior art will permit and 15 be restricted only as hereinbefore pointed out or as their terms demand.

I claim as my invention:

1. The combination with a polyphase induction motor, and a combined frequency 20 changer and phase-converter connected thereto, whereby relatively low-torque conditions are produced at certain critical speeds, of means for controlling the frequency of the current delivered to said induction motor, and means for so regulating the voltage impressed thereupon that the ratio 25 of said voltage to said frequency is increased while said induction motor is passing through its critical speeds.

2. The method of accelerating a polyphase induction motor from a combined frequency changer and phase-converter, which 30 consists in independently regulating the frequency of the current delivered to said induction motor and the voltage impressed thereupon in such manner that the ratio of 35 said voltage to said frequency is increased while said induction motor is passing through its critical speeds.

3. In the combination of a polyphase induction motor fed from a frequency changer connected to a single-phase source of supply, 40 said motor having, by reason of said connection, points of low-torque or critical speed 45 in its acceleration range, the method of accelerating said motor, which consists in increasing the ratio of the applied voltage to frequency at such points of critical low-torque speed.

4. In the combination of a polyphase induction motor fed from a frequency changer connected to a single-phase source of supply, 50 said motor having, by reason of said connection, points of low-torque or critical speed 55 in its acceleration range, the method of accelerating said motor, which consists in temporarily strengthening the field of said induction motor while it is passing through said low-torque points.

5. In the combination of a polyphase induction motor fed from a frequency changer connected to a single-phase source of supply, 60 said motor having, by reason of said connection, points of low-torque or critical speed 65 in its acceleration range, the method of ac-

celerating said motor, which consists in increasing the ratio of the applied voltage to frequency at such points of critical speed, and using said points of increased ratios as accelerating speeds only.

70

6. In the combination of a polyphase induction motor fed from a frequency changer connected to a single-phase source of supply, 75 said motor having, by reason of said connection, points of low-torque or critical speed 80 in its acceleration range, the method of step-by-step acceleration of said motor, which consists in changing from one speed to another, in each acceleration-step, by first raising the voltage impressed on said motor, 85 and thereafter increasing the frequency of the current supplied thereto.

7. In the combination of a polyphase induction motor fed from a frequency changer connected to a single-phase source of supply, 90 said motor having, by reason of said connection, points of low-torque or critical speed 95 in its acceleration range, the method of accelerating said motor, which comprises establishing, at starting, a ratio of impressed voltage on said motor to the frequency of current supplied thereto which is higher than the normal ratio of said quantities, and gradually decreasing the abnormality of said ratio during the progressive acceleration steps.

8. In the combination of a polyphase induction motor fed from a frequency changer connected to a single-phase source of supply, 100 said motor having, by reason of said connection, points of low-torque or critical speed 105 in its acceleration range, the method of accelerating said motor, which comprises establishing, at starting, a ratio of impressed voltage on said motor to the frequency of current supplied thereto which is higher than the normal ratio of said quantities, and gradually decreasing the abnormality of said ratio during the progressive acceleration steps, and finally operating said motor 110 with the normal ratio of said quantities.

9. In the combination of a polyphase induction motor fed from a frequency changer connected to a single-phase source of supply, 115 said motor having, by reason of said connection, points of low-torque or critical speed 120 in its acceleration range, the method of accelerating said motor, which comprises establishing, at starting, a ratio of impressed voltage on said motor to the frequency of current supplied thereto which is higher than the normal ratio of said quantities, gradually decreasing the abnormality of said ratio during the progressive acceleration steps and further increasing, at each 125 critical speed, said ratio over that dictated by said gradually decreasing excess.

10. The method of accelerating an induction motor from a source of variable frequency and variable voltage which consists 130

in varying first the voltage and then the frequency during each step of the acceleration of said induction motor.

11. The method of accelerating an induction motor associated with a frequency changer which consists in taking steps tending to vary first the voltage and then the

frequency of said frequency changer during each step of the acceleration of said induction motor.

10 In testimony whereof, I have hereunto subscribed my name this 31st day of July, 1918.

RUDOLF E. HELLMUND.
